W. M. SHEEHAN

HOPPER CAR DOOR

Filed Nov. 11, 1922

UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

HOPPER-CAR DOOR.

Application filed November 11, 1922. Serial No. 600,336.

To all whom it may concern:

Be it known that I, WILLIAM M. SHEEHAN, a citizen of the United States, residing at St. Louis, Missouri, have invented a certain 5 new and useful Improvement in Hopper-Car Doors, of which the following is a full, clear, and exact description, such as will enable others, skilled in the art to which it appertains, to make and use the same, reference being had to the accompanying drawings, forming part of this application.

My invention relates to railway rolling stock and consists in an improved door construction especially adapted for use in hopper cars.

The objects of my invention are to provide a rigid door having suitable hinge butts, reinforcements and operating mechanism brackets, without reducing the clearance of 20 the door above the rails and without raising the bottom of the hopper or decreasing the desirable dimensions for these parts.

I employ a cast door to attain these objects and am thus enabled to provide an efficient design of reinforcements and other parts, without being limited by standard sizes of structural shapes, the location of rivets or bolts, and without interrupting the smooth upper surface of the door.

30 In the accompanying drawings illustrating a selected embodiment of my invention,

Figure 1 is a top view of my improved door.

35 Figure 2 is a side view thereof. Figure 3 is a transverse section through a hopper car showing the door in raised position and sectioned on the lefthand side and showing the door in lowered position 40 as seen from one end thereof on the righthand side.

As above mentioned, the door preferably consists of a one-piece casting having a smooth hopper closure portion 1, one edge 45 of which is curved upwardly at 2, whereby the hopper capacity is increased, and hinge butts 3 are formed along this upwardly curved edge of the door. A reinforcing rib 4 is formed at each side of the door and 50 extends across the side thereof from front to rear. Intermediate the sides of the door, ribs 5 are provided, each merging into one of the hinge butts 3. Reinforcing ribs 6 are

provided intermediate the door front and rear and merge into ribs 4 and 5 where they meet the same.

The front of the door opposite the hinge butts is provided with a downwardly and inwardly depending flange 7 at the lower end of which a reentrant flange 8 is formed. The door body 1 and flanges 7 and 8 form a box-like structure open on one side which affords a rigid structure for this unhinged end of the door which is unprotected and is subjected to the dropping of material loaded in the car. At the ends of flanges 7 and 8, the box-like structure is closed by portions 9 which form an enlargement of the corresponding ends of ribs 4. The angular disposition of rib 7 is such that when the door is open, as shown in the righthand side of Figure 3, the rib will be approximately horizontal and a greater opening of the door is thereby obtained than if the rib was to extend perpendicularly to the door body 1.

Formed on the ends of the door adjacent flange 7 are operating mechanism brackets 10 which are provided with openings, the axes of which are inclined from the surface of body 1 and extend transversely of the axes of the hinge butts 3. By forming these brackets 10 integrally with the ends of the door, I avoid the punching of holes in the reinforcing ribs and the twisting of metal which would be the natural result of attempting to apply these brackets to the door if they were separately formed and had to be riveted or otherwise secured thereto.

While it would be possible to apply hinge butts, reinforcements and operating mechanism brackets, which would be separately formed from forgings or the like, in order to secure the same strength in such parts, it would be necessary to make them heavier than the parts here shown and, in order to secure permanency of assembly, it would be necessary to use a large number of securing means such as rivets or bolts. At best, such an assembly would not provide the rigid construction resulting from my one-piece door, and the upper surface of the door would have a corresponding number of obstructions to impede the discharge of the material, and to collect air and water which would result in damage from corrosion and freezing.

In addition to these advantages, the door shown may be provided at less expense than built-up doors of inferior quality.

Various modifications in the shape of the door and in the disposition of the hinge butts, reinforcing ribs, and operating mechanism brackets, may be made without departing from the scope of my invention as expressed in the following claims.

10 I claim:

1. A hopper car door consisting of a one-piece casting comprising a hopper closure, hinge butts, reinforcing ribs, and brackets for attaching operating mechanism.
- 15 2. A hopper car door consisting of a one-piece casting comprising a hopper closure, reinforcing ribs along two sides and the front thereof, brackets for attaching operating mechanism at the ends of the front flange, a plurality of hinge butts spaced along the fourth side thereof, and reinforcing ribs extending from said hinge butts to the flange on the front of the door.
- 20 3. In a one-piece hopper door, hinge butts disposed along one edge thereof, and a depending and reentrant flange along the opposite edge thereof forming a box-like reinforcement open on one side.
- 25 4. In a one-piece hopper door, hinge butts disposed along one edge thereof, a depending and reentrant flange along the opposite edge thereof forming a box-like reinforcement open on one side, and ribs extending

through the open side of said reinforcement transversely of the same and merging with the other side of said box-like reinforcement.

5. In a one-piece hopper door, hinge butts disposed along one edge thereof, and a reinforcing flange formed on the opposite edge thereof and inclined downwardly and rearwardly from the upper face of the door.

6. In a hopper car, a hinged door, and a reinforcing flange formed on the edge thereof opposite the hinges and inclined downwardly and rearwardly from the upper face of the door at an angle which will approximate the horizontal when the door is open.

7. In a one-piece hopper door, hinge butts disposed along one edge thereof, a depending and reentrant flange along the opposite edge thereof forming a box-like reinforcement open on one side, and operating mechanism brackets formed on the ends of said reinforcement.

8. In a one-piece hopper car door, a hopper enclosure curved upwardly at one end, hinge butts formed on the edge of said curved end with their axes substantially above the door plane, brackets formed on the sides of the door near the opposite end thereof and provided with operating mechanism openings having axes disposed transversely of the axes of said hinge butts.

In testimony whereof I hereunto affix my signature this 27 day of October, 1922.

WILLIAM M. SHEEHAN.
